D. WEINBERG

ADJUSTABLE ROOF FLANGE

Filed May 13, 1927

Fig. 2.

A technical line drawing of a rectangular frame, labeled 'FIG. 3. 6'. The frame is defined by a thick outer line. Inside, there is a central rectangular slot with a vertical line extending from its center. A hinged door, labeled '6', is attached to the right side of the frame, positioned above the central slot. The door is shown in an open position. The entire assembly is rendered with fine hatching lines, particularly along the top and bottom edges of the frame and the door.

UNITED STATES PATENT OFFICE.

DAVID WEINBERG, OF ROCKAWAY BEACH, NEW YORK, ASSIGNOR TO PARAMOUNT ROOF FLANGE CORPORATION, A CORPORATION OF NEW YORK.

ADJUSTABLE ROOF FLANGE.

Application filed May 13, 1927. Serial No. 191,098.

The present invention relates to improvements in adjustable roof flanges adapted for sealing the joint between the roof and soil or other pipes passing therethrough.

5 It has for its object to provide a unitary device which may be quickly and easily applied to roofs of different pitches and requiring no more than the tapping of its collar or ring member into contact with the 10 pipe to secure an effective leak-proof seal.

In the carrying out of my invention it has been my particular aim to provide a new article of manufacture embodying a roof flange of suitable metal in which an orifice 15 of proper size is formed and a collar which is composed of ductile material, such as lead, having an interlocking water-tight connection with the flange, this collar being preferably molded with certain beads which im- 20 part the necessary strength and rigidity to it and permit its mouth to be hammered without causing the material to split or break.

Other objects and advantages of the in- 25 vention will be hereinafter set forth and the novel features thereof defined by the appended claims.

In the accompanying drawings:—

Figure 1 is a sectional view through a de- 30 vice constructed in accordance with my in- vention disposed in operative position in relation to the roof and soil pipe passing therethrough;

Figure 2 is a side elevation of the device 35 alone, partly broken away and shown in section;

Figure 3 is a view on the line 3—3 of Figure 2 previous to the conjoining of the flange and collar; and

40 Figures 4 and 5 are elevation views showing graphically the adaptability of the de- vice to pipes passing through roofs of differ- ent pitches.

Like reference characters designate cor- 45 responding parts throughout the several figures of the drawing.

Referring to the drawing, A designates the 50 roof of a building provided with an opening B through which the soil pipe C passes. The device forming the feature of this in- vention is adapted to be applied about the pipe as shown in Figure 1 so as to effectively seal the roof against leakage at this point.

Numerous devices for this purpose have 55 heretofore been proposed but in the majority

of instances the articles have been made up of separable parts which require assembling on the job, soldering together, packing or calking, and other operations which deprive them of the advantages of quick and ready application and permit of leakage unless the assembling is carefully carried out.

My device, on the other hand, is designed as a unit or integral structure and as depicted in the drawing comprises a flange or plate 1 of suitable metal such as sheet copper, galvanized sheet iron or sheet lead, having an orifice 2 therein and a collar member 3 surrounding said orifice. This collar is of ductile material such as lead, preferably 70 molded in such configuration as to provide a reinforcing bead 4 around the top, a corresponding bead 5 at the base, and connecting ribs 6, these tending to strengthen the collar against fracture when hammered into 75 cooperation with the pipe, as later referred to. The collar is also formed in this molding operation with a depending lip or flange 7 at its base and with a groove 8 in the bottom of the bead 5 to receive the upturned 80 flange 9 formed about the orifice 2 of the plate 1. These two parts are joined together by seating the flange 9 in the groove 8 and bending outwardly the lip 7 against the bottom of the plate, such operation being pref- 85 erably performed by suitable pressure apparatus, so as to insure the formation of a solderless leak-proof joint at this point. It is contemplated that the groove 8 shall be slightly smaller than the flange so that in 90 the pressing operation this flange will be forced into the metal to a certain extent and insure the character of joint above referred to.

The unit thus formed is placed over the 95 pipe and the collar hammered about the bead 4 until snug contact is made with the pipe all about the same, the extent of de- formation of the collar by this process de- pending upon the pitch of the roof. It will 100 be noted that the walls of the collar are nor- mally angularly related to the plate 1, the opening at the top of said collar being truly circular while the opening at the base is relatively larger and ellipsoidal. This en- 105 ables the device to be universal in applica- tion to varying pitched roofs and standard- ized for different diameters of pipes. Owing to the construction of the unit it may be inexpensively manufactured which is of 110

material advantage in an article of this character.

Having thus described my invention, what I claim as new and desire to secure by Letters Patent is:—

1. As a new article of manufacture, an adjustable roof flange comprising a flange plate having an orifice therein and a collar of ductile material attached to the plate about the edge of the orifice by an interlocking joint, said collar being formed at its top with a hammer receiving reinforcing bead adapted to prevent fracture of the edge of the collar when said edge is forced inwardly, and means extending from said edge to the plate for reinforcing the collar at the intermediate portion against fracture when forcing the edge inwardly as aforesaid.
2. As a new article of manufacture, an adjustable roof flange comprising a flange plate having an orifice therein and a collar of ductile material interlocking with the edge of the orifice and formed with spaced annular and cross reinforcing beads.
3. As a new article of manufacture, an adjustable roof flange comprising a collar having exterior top and bottom reinforcing beads connected by intermediate ribs and

formed at its base with an annular vertically extending groove in the bottom bead and a flange plate having interlocking means seated in said groove to provide a leak-proof joint in the plane of the plate.

4. As a new article of manufacture, an adjustable roof flange comprising a collar having spaced annular beads and cross ribs and formed at its base with a groove and an adjacent bendable flange, a flange plate having an orifice therein the edge of which is upturned to provide a flange seated in said groove, the bendable flange on the collar coacting with the plate at the opposite side of its flange and effecting an interlock between the collar and the plate to provide a leak-proof joint.

5. As a new article of manufacture, a roof flange comprising a collar of ductile material molded with reinforcing beads at the top, bottom and sides, a flange plate having an orifice therein, the edge of the orifice being flanged to coact with the base of the collar and pressed into the material of the same to form a leak-proof joint around the orifice.

In testimony whereof I affix my signature.
DAVID WEINBERG.
